CLAIM

The ornamental design for a shoe, as shown and described.

DESCRIPTION

FIG. 1 is a front perspective view showing my new design; FIG. 2 is rear perspective view thereof;

FIG. 3 is another rear perspective view thereof;

FIG. 4 is a front view thereof;

FIG. 5 is a rear view thereof;

FIG. 6 is a left-side view thereof;

FIG. 7 is a right-side view thereof;

FIG. 8 is a top plan view thereof; and,

FIG. 9 is a bottom plan view thereof.

The broken lines depicting a shoe represent environment that forms no part of the claimed design.
